By John S. Barker Atty.

UNITED STATES PATENT OFFICE.

EUSTACE CARLILL BRIERLEY, OF BATH, ENGLAND.

POLISHING DEVICE.

Application filed June 11, 1925. Serial No. 36,537.

To all whom it may concern:

Be it known that I, EUSTACE CARLILL BRIERLEY, British subject, residing at Vale Lodge, Weston Park, Bath, Somersetshire, England, have invented a new and Improved Polishing Device, of which the following is a specification.

This invention comprises a new or improved polishing device and has reference 10 to that type of device which embodies a stock or handle and a pad having a covering or polishing surface of wash leather or other suitable fabric or material, such a device being particularly applicable to manicure purposes.

When using a device of the above class for polishing the finger nails it has been found that the pad as hitherto constructed causes considerable friction and the nails become heated even though a comparatively small pressure is applied to the pad. Moreover, whether applied to manicure purposes or other purposes the pads as hitherto constructed have not sufficient resiliency to 25 perform the cleansing or polishing purpose effectually or for any length of time without the application of considerable pressure, as, after use for a short period, the pads become hard and hence wanting in efficiency.

30 A feature of the present invention consists in the provision of a polishing device which incorporates an inflatable pad member and means for inflating said pad as and when desired.

35 Another feature of the invention consists in a polishing device comprising a pneumatic cushion having assembled over same a cover which constitutes or is provided with a working or polishing surface, said cushion having incorporated therewith a pump for the inflation thereof, and the whole being mounted in a self-contained manner upon or within a suitable stock or holder.

40 A further feature resides in the provision in conjunction with the pump of a valve adapted to be operated for releasing the air from the cushion when desired.

45 Further features of the invention will be hereinafter more fully described.

50 For the purpose of more fully describing the nature of this invention, reference will now be made to the accompanying drawings, wherein:—

55 Fig. 1 is a perspective view of a polishing device constructed in accordance with the present invention.

Fig. 2 is a longitudinal section through the device.

Fig. 3 is a cross section through the device.

In one convenient method of carrying out the invention, same will be described as applied to a manicure polishing pad. A stock or holder 1 of metal, wood or other suitable rigid material is in the nature of a plate, 65 preferably of elliptical shape in plan having its edges overturned as at 1^a so as to form said stock to inverted channel shape in plan. The stock 1 is formed at its two ends with downwardly projecting lugs 1^b, 70 1^c, one of said lugs 1^b having a plain hole while the other 1^c has a screw-threaded hole for the reception of a screw 2.

Assembled lengthwise beneath the stock 1 is an air pump or inflator 3 of the customary 75 single-acting type, said pump being fixed in position at one end by inserting a reduced boss portion 4^a of a plug or cap 4 fixed at the one end of the pump barrel into the plain hole in the lug 1^b, and at the other 80 end by screwing up the screw 2. The pump rod 5 which is adapted to be reciprocated within the pump barrel 3 carries at its inner end a suitable piston and at its outer end a knob or handle, said knob projecting on 85 the outer side of the lug 1^b.

Near the end of the pump barrel opposite to that at which the piston rod projects is a small port or perforation 6 through which air is pumped into a pneumatic cushion 7 90 for the purpose of inflating same. This cushion is preferably of suitable elastic material and conveniently of approximately cigar shape, and is suitably secured at its ends to the pump in such a manner that the 95 pump passes through same.

Surrounding the cushion in a readily detachable and interchangeable manner is an outer cover 8 of wash leather or other suitable material which provides the polishing 100 or working surface of the pad, said cover being secured by adhesive or otherwise to, or having assembled therein, a rigid plate 8^a of elliptical shape, which is adapted to fit within the side flanges 1^a of the stock 1 so as to retain the cover 8 in the required position. The cover 8 is tapered at its ends so as to cause same to conform to boat shape when the cushion is inflated therein.

110 The port 6 in the pump barrel is covered with a piece of rubber-tubing 9 which functions in the manner well known to prevent

return of air from the cushion to the pump. A portion of the length of the pump barrel at the handle end may advantageously be slightly enlarged in diameter as at 10 to ensure free inflow of air to the front of the piston.

In order to permit of the ready deflation of the cushion a plug-like extension 11 is secured at the closed end of pump barrel, 10 said extension having an L shaped air passage 12 therein, one arm of which passage opens out at the circumferential face of the plug while the other extends axially to an annular chamber or recess 13 in the plug 15 end within which recess is fitted a valve 14. This valve 14 is retained within the recess 13 by turning over the edge of said recess as at 13^a, said valve being capable of a small amount of movement in an axial direction.

20 When the screw 2 is tightened up, the valve 14 is pressed on to its seating and closes the passage 12, and in order to deflate the cushion all that is necessary is to unscrew the screw 2 to a small degree when 25 the air will pass from the cushion by way of the passage 12 and out from the end of the plug 11 past the valve 14.

The stock 1 may have a handle portion 15 screwed or otherwise secured thereto, or 30 said handle may be an integral portion of the stock.

I claim:—

1. A polishing device embodying an inflatable pad and a pump for inflating the 35 same arranged within the pad substantially as described so as to produce a single, self-contained, unit.

2. A polishing device embodying a rigid holder, an inflatable pad and a pump, the 40 pump being within the pad so as to constitute therewith a single self-contained unit, and the pump being supported in the holder, thereby uniting the pad thereto.

45 3. A polishing device comprising in combination a rigid holder constructed for convenient manipulation, an inflatable pad, a pump for inflating the pad arranged to constitute therewith a single unit, the pump being supported by the holder and uniting 50 the pad thereto, and a cover for the pad

united to the holder independently of the said pad and pump unit.

4. A polishing device, comprising in combination a stock or holder, a bag-like cover member carried by said stock, a pneumatic cushion of elastic material assembled within said cover and a pump carried by said stock and protruding into the cushion for inflating same. 55

5. In a polishing device, the combination 60 of a rigid holder constructed for convenient manipulation, an inflatable pad, and a pump for inflating the pad detachably secured at its opposite ends to the holder; the pump having a handle by which it may be worked that is freely movable independently of the supporting connections for the pump. 65

6. In a polishing device, the combination 70 of a holder having a peripheral flange, an inflatable pad adapted to be supported below the holder and within the confines of the said flange, a pump for inflating the holder having supports at its opposite ends in the flange of the holder, the pump having a handle by which it is operated extending through the flange, a valve controlling an exit through which the pad may be deflated, the valve having operating means extending through the flange of the holder, and an elastic cover for the pad carried 75 by the holder.

7. In a polishing device, a stock, a pneumatic cushion carried by said stock, a pump mounted on the stock for inflating said cushion, said pump comprising a tubular pump 85 barrel and reciprocative plunger, and said barrel extending completely through the pneumatic cushion and having an air release valve for effecting deflation of the cushion.

8. In a polishing device, a stock or holder, a pneumatic cushion carried thereby, a cover assembled over said cushion, a pump barrel, with reciprocating plunger detachably mounted upon the stock, an air release valve for deflating the cushion and means 95 for controlling said valve, said valve controlling means also functioning as means for fixing the pump with cushion in position upon the stock or holder.

EUSTACE CARLILL BRIERLEY.
